UNITED STATES PATENT OFFICE.

FREDERICK WILLIAM ANDREW, OF BROOKLYN, NEW YORK, ASSIGNOR TO EISEMANN MAGNETO CO., OF BROOKLYN, NEW YORK, A CORPORATION OF NEW YORK.

LOCKING DEVICE FOR IMPULSE-STARTERS.

1,281,750.

Specification of Letters Patent. Patented Oct. 15, 1918.

Application filed June 29, 1918. Serial No. 242,613.

To all whom it may concern:

Be it known that I, FREDERICK WILLIAM ANDREW, a citizen of the United States, and a resident of the city of New York, borough 5 of Brooklyn, county of Kings, and State of New York, have invented certain new and useful Improvements in Locking Devices for Impulse-Starters, whereof the following is a full, clear, and exact specification.

10 My invention relates to devices known in the art as "impulse starters", by means of which a rapid rotatory motion is imparted to the armature of a magneto at the moment of starting an internal combustion engine 15 to produce a spark of sufficient intensity to ignite the explosive charge in the cylinder of the engine. These impulse starters are usually composed of a driven part fixed to the magneto shaft, a driving part rotatably mounted thereon, and of a spring, which is tensioned by rotating the driving part in advance of the driven part, and then, reacting, propels the latter rapidly through a part of its revolution, approximately equal to the 20 advance of the driving part. They are designed to operate as a coupling after the engine has been started, the driven and the driving parts of the device being usually connected by the aforementioned spring. The 25 functioning of these devices depends upon the activity of the spring, constituting in some instances, the only connection between the driven and the driving parts. Consequently, the breaking of the spring renders 30 the impulse starter inoperative, not only for the starting of the engine, but also as means for transmitting rotatory motion from the driving shaft to the shaft of the rotatory part of the magneto, and the magneto, and the ignition, and consequently also the engine, are 35 thereby put out of action.

40 The object of my invention is to provide means for locking together the driving and the driven parts of the starting devices, these means to be inactive when the starting device is in operative condition, but ready to be employed when the actuating spring breaks, or is so weakened as to cause 45 serious lag in the ignition, or whenever the starting device is rendered inoperative from other causes.

The forms of construction of the locking means are largely determined by the constructions of the starting devices, upon 50 which they are to be used; the forms, illus-

trated in the accompanying drawings, and hereinafter described, show the principal features of all locking means, constructed according to my invention, and the method of their applications to the starting devices. 60

In the accompanying drawings—

Figure 1 is a top view, and

Fig. 2 is a front view of an impulse starter, with a locking device constructed, and applied thereto, according to my invention, part of the driven member of the impulse starter being broken off in Fig. 1 to show the parts of the locking device engaged therewith when in operative position; 65 the inactive position of the locking device 70 being shown in dotted lines in Fig. 1;

Fig. 3 is a plan view of the locking device, and

Fig. 4 a sectional view on line 4—4 indicated in Fig. 3; 75

Fig. 5 is a top view, and

Fig. 6 a front view, of another form of impulse starter, showing my improved locking device applied thereto, the locking device being shown in its inactive position; 80

Fig. 7 is a plan view of the locking device, used on the impulse starter shown in Figs. 5 and 6, and

Fig. 8 a sectional view thereof on line 8—8 indicated in Fig. 7; and 85

Fig. 9 is a side view of the impulse starter shown in Figs. 5 and 6 with the locking device in acting position.

The construction of the locking device is 90 conditioned by the construction of the impulse starter, to which it is to be applied, and by the requirement that it should be so applicable to the impulse starter as not to interfere, in any way, with its operation, while the impulse starter is being used for 95 its contemplated purpose, and by the requirement that it should be readily available for locking together of the driven with the driving part of the impulse starter, *i. e.* for locking the parts securely together, when the 100 spring breaks, or the starting device is rendered inoperative from any other cause.

As shown in the drawings, the locking device, designated 11 in Figs. 1 to 4, is made in the form of a forked bolt, and is secured 105 by the set screw 12 to the driving part 13 of the impulse starter, illustrated in Figs. 1 and 2.

The locking device 11 may be stamped in the form shown in Fig. 3, of sheet metal, a 110

hole 12 punched therein, and then curved correspondingly to the circumference of the part of the impulse starter to which it is to be secured. The hole 12 is punched as shown 5 in Figs. 3 and 4, to fit the screw 12^a and to make the locking device turnable thereon, and the edges of the prongs 11^a are rounded. A bore, screw-threaded correspondingly to the thread of the screw 12^a, is made in the 10 driving part 13, and in the driven part 14 two bores 18 are made, corresponding in size and in position to the prongs 11^a of the locking device. The bore for the set screw 12 is made in the driving part 13 beyond, and near to, one of the cams 16, and the bores in the driven part 14 beyond, and near to one of the recesses 17. In this position the locking device when in its inactive 15 position, shown in dotted lines in Figs. 1 and 2, does not interfere with the operating of the impulse starter in any way, and when it becomes necessary to use it, it can be readily set into its position shown in full lines in Figs. 1 and 2, by turning the bolt 20 11 and setting its prongs 11^a into the bores 18 in the driving part, whereby the driven and the driving parts are locked together in the same relative position as they would be held by the spring under normal conditions. 25

30 The selection of the point where the locking device is to be applied to the impulse starter, illustrated in Figs. 5, 6 and 9, presents less difficulty for decision, the greater width of the driving part 13 affording ample space for the locking device to be mounted thereon, so as not to interfere in any way with any of the operating parts of the impulse starter. The circumstance, however, that the driven and the driving parts 35 of this impulse starter are of the same size, requires the form of the locking device to be modified, as shown in Figs. 7 and 8, by bending the prongs 11^a at an approximately right angle, and to make the bores 18^a in the peripheral surface of the driven part 14. 40 In other respects the construction, and the operative and inoperative positions, of this locking is the same as that described above. A screw-threaded bore, into which the set screw 12 is fitted, is made in the driving part 13, preferably some distance beyond the cam 19. The inactive position of the locking device is shown in Figs. 5 and 6. The two bores 18^a in the driven part 14 are 45 located beyond and near the slot 21, in which the trip lever of the pawl of the interior mechanism of the impulse starter operates. This position is selected for the reason that if the driven and the driving parts are

locked together in this relation to each other, 50 the tooth on the interior hub of the driving part, wherewith the above-mentioned pawl engages, is then in contact with the face of the cam on the hub of the driven member, which limits the extent of the rotary motion of the driving part in advance 55 of the driven part, and, consequently, takes up the driving strain and relieves to that extent the locking device, whose function then is confined to the maintaining of the 60 driven and the driving parts in that position. 65

These examples of constructing and using the locking device have been selected to show the varying conditions, which must be met, 70 and also the way of meeting them by correspondingly modifying the details of the locking device and of its application to impulse starters differing in details of their 75 construction. 80

I claim as my invention:

1. The combination with an impulse starting device, comprising a driven part, adapted to be fixed on the rotatory part of a magneto, a driving part rotatably mounted thereon, and a spring, yieldingly connecting them, of manually operable means, movably secured to one part, and adapted to be set in engagement with the other part, for locking together the driving and the driven 85 parts of the impulse starter; substantially as herein shown and described.

2. The combination with an impulse starting device, comprising a driven part, adapted to be fixed on the rotatory part of a magneto, a driving part rotatably mounted thereon, and a spring, yieldingly connecting them, of a locking device comprising a recess in one part, and a bolt, turnably secured to the other part, the bolt being fitted into 90 the recess, and when turned and set therein locking together the driving and the driven part of the impulse starter; substantially as herein shown and described.

3. A coupling device, comprising a driven part, a driving part rotatably mounted on the driven part, and manually operable coupling means movably secured to one of the two parts, means on the other part adapted to engage with the coupling means, 105 and means for fixing the coupling means in active, or inactive, position; substantially as herein shown and described.

FREDERICK WILLIAM ANDREW.
